UNITED STATES PATENT OFFICE

HENRY H. SCHMIDT, OF CHICAGO, ILLINOIS

TOY GUN

Application filed February 19, 1930. Serial No. 429,678.

My invention relates to toy guns, and more particularly to those which are designed to shoot paper projectiles or rubber bands, and my main object is to provide a gun of this kind which is of a sturdy open-work construction.

A further object of the invention is to build into the structure of the novel gun a rigid bracing element conducive to hold the shape of the gun against distortive or injurious influences.

Another object of the invention is to combine the frame and bracing elements of the gun with a positive locking arrangement to prevent relative motion therebetween.

An additional object of the invention is to extend the bracing element to form a projectile guide.

A significant object of the invention is to design the barrel of the gun with extension means effective to lend greater attention to the rubber band or bands constituting the motive source.

With the above objects in view and any others that may suggest themselves from the specification and claims to follow, a better understanding of the invention may be had by reference to the accompanying drawings, in which—

Figure 1 is an elevation of the gun as extended showing the same in position to be discharged;

Fig. 2 is a plan view of the article;

Figs. 3 and 4 are, respectively, sections on the lines 3—3 and 4—4 of Figure 1;

Fig. 5 is a section on the line 5—5 of Figure 2; and

Fig. 6 is a perspective view showing the manner of applying an extension to the gun barrel.

Referring specifically to the drawings, 10 denotes the barrel portion, 11 the stock portion, and 12 the handle portion of the novel toy gun. These portions constitute a frame made from a single length of steel strip stock, bent to simulate a real gun in form and joined by welding 13, which is in an inconspicuous location.

The upper and lower sections of the stock 11 receive between them a pair of laterally

spaced plates 14 of stiff sheet metal, these serving to brace the stock against collapse. At the rear, the plates 14 are held together by a rivet 15 while at the front holes 15a are made in registration for an additional rivet, in case it is found necessary. The holes in the plates are preferably countersunk, as indicated at 15b, to seat the rivet heads flushly. Thus, the surface of each plate is flat in its entirety, facilitating the application of a label or covering bearing advertising matter.

The edges of the sections 11 are cut at the rear with notches 11a and toward the front with shallow recesses 11b. The side plates 14 are extended with in-bent tabs 14a and 14b seating respectively in the rear and frontal notches 11a and 11b, the bottom tabs 14b being long in order to conform to the length of the recesses 11b thereat. The tabs of the side plates 14 overlie the sections 11 of the frame and serve to hold them in rigid contact with the side plates. At the same time, the seating of the tabs in the notches prevents the side plates from collapsing toward each other.

While the notches 11a are cut in a directly transverse direction, it will be noted that the frontal ends of the recesses 11b are undercut, as clearly indicated at 11c. This construction locks the frontal portion of the plates 14 to the stock without the need of a rivet in the holes 15a, maintaining such portions against separation from the stock. However, should the cutting of the profile of the undercut recess portions dull in manufacture, it is not necessary to discard the product, as the rivet for the holes 16 may be provided to replace the function of the undercut recess ends. As noted, the under cut notch ends are defined by spurs. These may be pressed in upon the plates as indicated at the bottom of Figure 3 to more securely retain the plates; also, this operation retracts the points of the spurs from catching on clothing or other objects.

The sides 14 are adapted to receive between them a trigger 16, which is medially pivoted on the rivet 15. The lower portion of the trigger extends through a slot 11d in the

frame to be cut with a notch 16a in the rear and a shoulder 16b in the front, and the upper end rises through a slot 11e in the frame and is made in plain form. A rubber band 17 is adapted to be hooked with one end of its loop in the notch 16a of the trigger 16, tensioned in forward direction and wrapped about a lug 10b projected from the barrel 10 and brought back along the top of the latter to hook with the other end of its loop on the upper end of the trigger. The upper sections of the rubber band lie on both sides of projectile guides 18 extended from the sides 14, which are closely grouped along the center of the stock. The guides 18 are substantially vertical and are formed out of inward bends made from the sides 14 above the upper stock section 11. The proper spacing of the guides 18 permits the insertion with light pressure of a thin cardboard disk 19 between them which serves as a projectile, the disk being loosely disposed for resting on the stock. The pulling of the trigger 16 in the usual direction to discharge, releases the upper section of the rubber band 17 to strike and hurl the disk 19 forward, the upper edges of the guides 18 meeting the stock plane with a gradual curvature whereby to present no obstruction to the progress of the rubber band. The upper edge of each side plate 14 is cut down as indicated at 18a to independently define the guides 18, that these may be gathered or separated to the proper spacing without warping the side plates or weakening the hold of their tabs.

By stretching the rubber band 17 over a longer course it may be given greater tension and therefore quicker discharge, this resulting in the sending of the projectile on a longer flight. I provide a simple expedient for stretching the rubber band in the form of a barrel extension 20. This extension is of the same general form as the barrel, the latter being made with a squared front end 10a and the extension with a squared rear end 20a to seat the extension firmly endwise of the gun barrel. The front end 10a of the latter is struck forward with the lug 10b, which when the extension is not used, serves to space the sections of the rubber band 17 laterally, the lug being flared in an outward direction to also serve as a retainer for such sections. For the purpose of the extension 20, however, the lug 10b also forms an anchor device in connection with a perforation 20b made in the rear end 20a of the extension. The perforation 20b is flared in an upward direction to a dimension easily clearing the outer end of the lug 10b, whereby to permit the extension to be mounted against the end of the gun. However, before the extension can seat on the latter, it must be raised even with the gun barrel, so that it seats the inner or neck portion of the lug 10b in the narrow

or lower portion of the perforation 20b of the extension, locking the extension from endwise separation from the gun barrel.

In order that the extension 20 may be held in a position to retain the locking engagement just described, it is made with its bottom elongated as a strip 20h to underlie the gun barrel. Here the doubled extension and gun barrel strips are made with longitudinally spaced perforations 20c, 20d, and 10c, 10d, respectively. The perforations 20d and 10d register, and an up-struck lug 20e passes from the extension strip into the barrel bottom by way of the perforation 10d, serving to lock the extension and the barrel from endwise separation. However, to make the connections permanent, a screw 21 is applied by way of the perforations 20c and 10c, which register, through the doubled strips to receive a nut 22 on the inside of the barrel for securing purposes. The front end of the extension 20 is made with a lug 20f struck forward from a perforation 20g, precisely as the front end of the barrel, in order to accommodate the rubber band 17 as stretched to greater length in the same manner as in the previous instance, and as clearly shown in Figure 1. The extension is so made that it may receive a further like unit to make the gun barrel still longer if desired, the means to apply such unit being similar to those already described and the units being interchangeable.

In dividing the sections of the rubber band upon the end of the barrel or its extensions, the tensile property of the sections is also divided, that is, tension from one section is not transmitted to the other section. This division is assured by the wrapping of the band about the barrel lug 10b—or extension lug 20f—at the dividing zone. Thus, the life of the band is prolonged, since the lower section is always under normal tension and does not receive changes in tension as does the upper section; on the other hand, the latter section can be kept slack while not in use.

While paper disks are preferable as projectiles on account of their nominal cost, swift flight and value when printed with educational or advertising matter, it is easily possible to use the novel gun for shooting rubber bands. In this respect, the lug 10b—or 20f—serves as an anchor for a rubber band applied from below, as in the previous case, and for another band applied from above and in front of the bottom band. The two bands again appear as in Figure 1, but in pulling the trigger, the upper band is released for flight, and the lower one remains in place.

In forming the trigger 16 with the frontal shoulder 16b, an advantage in assembly the trigger with the stock is had, since the trigger perforation for the rivet 15 can more readily be aligned with the holes in the plates

when the shoulder rests on the front end of the bottom slot 11d. Another structural advantage lies in the flexibility of the handle

12. Where the user's hand is too small for 5 the convenient reach of the trigger, the handle as a whole can be forced forward to advance the position of the hand.

It will be seen that the novel toy gun is an article which is not only simple in appearance but rigid and firmly assembled. The 10 bracing plates 14 not only prevent the gun frame from collapsing but are joined to the same by the particular means described whereby to remain properly spaced and protect the frame from distortion or loss of shape 15 in case the article is roughly handled, or falls to the floor. The extension unit or units may be kept separately during the ordinary use of the gun, but may be quickly and easily applied 20 in case the barrel is desired to be lengthened for the purposes described. Finally, the material entering into the construction of the device is simple and inexpensive, and requires but ordinary equipment to lend 25 it the ultimate form.

I claim:

1. A toy gun comprising a band looped to simulate the form of a gun, upper and lower band portions occupying the zone of the stock 30 and being laterally notched, side wall plates for the stock fitted between said band portions, and extensions of the plates seating in said notches to limit the inward movement of the plates.

2. The structure of claim 1, and tabs continued from said extensions and bent upon the respective band portions.

3. The structure of claim 1, said notches having undercut ends to lock the plates from 40 separation from the stock.

4. The structure of claim 1, said notches having undercut ends to lock the plates from separation from the stock, and spurs defining such ends, said spurs being foldable upon the 45 plates to more fully lock them and confine the points of the spurs.

5. A toy gun comprising a band looped to simulate the form of a gun, upper and lower band portions occupying the zone of the stock 50 and slotted in a vertical plane, side plates applied to the stock, a horizontal pivot secured to said plates between the band portions, and a trigger mounted intermediate its ends on said pivot for oscillatory movement in the slots of the band portions, said trigger having a frontal shoulder limited by the frontal end of the slot in the lower band portion when the draw-portion of the trigger is advanced.

6. A toy gun comprising a band looped to simulate the form of a gun, upper and lower band portions occupying the zone of the stock, side plates applied to the stock, these being recessed in their top edges, and tongues defined by the recesses and rising over the upper 65

band portions to juxtaposed relation as guides for a projectile applicable therebetween.

7. A toy gun including a barrel formed from a frontally squared loop, and a looped 70 extension squared and applied endwise of the barrel to seat firmly as a confirmation of the latter.

8. The structure of claim 7, and means to lock the barrel and the extension from separation. 75

9. In a toy gun, locking means between the end of the barrel and an extension for the latter, comprising a flared tongue extended from the end of the barrel, and a perforated 80 rear wall of the extension applicable to such end, the perforation being tapered and with its wide end sufficient to permit the passage of the tongue when the extension and the barrel are assembled out of alinement, the 85 narrow end of the perforation receiving the neck of the tongue when the extension and barrel are alined whereby to lock the tongue against withdrawal from said wall.

10. The structure of claim 9, said barrel 90 end being a looped strap, and the tongue struck forward from the latter.

11. The structure of claim 9, a rearward strip from the extension and alongside the barrel, and means to fasten the strip to the 95 barrel.

In testimony whereof I affix my signature.
HENRY H. SCHMIDT.
